UNITED STATES PATENT OFFICE.

IRA S. DOWNING, OF INDIANAPOLIS, INDIANA, ASSIGNOR TO WALTER P. MURPHY, OF CHICAGO, ILLINOIS.

MEANS FOR SUPPORTING RAILWAY TRAIN-PIPES.

1,120,607.

Specification of Letters Patent.

Patented Dec. 8, 1914.

Original application filed May 1, 1912, Serial No. 694,418. Divided and this application filed December 31, 1913. Serial No. 809,735.

To all whom it may concern:

Be it known that I, IRA S. DOWNING, a citizen of the United States, residing at Indianapolis, in the county of Marion and State of Indiana, have invented certain new and useful Improvements in Means for Supporting Railway Train-Pipes, of which the following is a specification.

My invention relates to railway car train pipes and means for attaching the same to the cars.

One of the principal objects of the invention is to provide a suitable and inexpensive device for positively engaging a railway car train pipe, at or near its extremity for example, and firmly and rigidly anchoring the same to the under frame of the car so that the pipe cannot shift in the direction of its length. It has been customary to support train pipes on hangers which take a frictional or impositive grip on the pipe, with the result that the inertia of the pipe, when the train starts or stops, or when the car is bumped against another car in making up a train, causes the pipe to slip in the hangers and shift in the direction of its length. This frequently breaks the connection between the train pipe and the air reservoir and is objectionable for other reasons apparent to those familiar with the operation of railway trains. My invention prevents this longitudinal shifting of the train pipe.

A further object of the invention is to provide a device of this sort which, though supporting the train pipe at or near its extremity in order to minimize the leverage on the connection of the coupling, may be attached to one of the longitudinal sills of the car instead of to the end sill. It is customary to secure the hanger supporting the extremity of the train pipe to the end sill of the car. This is objectionable, particularly on freight cars having wood end frames, because the draft on the end sill is likely to loosen it, so that, if the train pipe is secured to the end sill, the pipe or the parts connected therewith are likely to be bent or broken.

A further object of the invention is to construct a device of this character so as to make it adjustable for cars of different construction, for example so that the identical devices can be used upon cars in which the longitudinal sills are at different distances

from the prescribed position of the train pipe; the distance of the train pipe from the longitudinal median line of the car being the same for all cars equipped under the requirements and regulations of the Master Car Builders' Association.

The invention has for further objects such other new and improved arrangements, constructions and devices relating to train pipes and means for securing the same to cars as will be hereinafter described and claimed. I do not, however, claim in this application broadly the expedient of dividing the train pipe into lengths or sections, joining the sections together by coupling elements and anchoring the coupling elements positively to the car, as this invention is claimed in my application Serial No. 694,418, filed May 1, 1912, of which the present application is a division.

The invention which is sought to be patented herein is illustrated, in certain preferred embodiments, in the accompanying drawings wherein—

Figure 1 is a fragmentary plan of the end of the under frame of a railway car having attached thereto a device for supporting the train pipe constructed in accordance with the invention; Fig. 2, a plan view of the device on a larger scale with the under frame of the car in part broken away; Fig. 3, a longitudinal sectional view of the parts shown in Fig. 2; Fig. 4, a detail, in perspective, of the adjustable coupling element; Fig. 5, a view similar to Fig. 3 showing a modified construction; Fig. 6, a sectional view taken on line 6—6 of Fig. 5, and Fig. 7, a detail, in perspective, of the coupling element forming part of the device shown in Figs. 5 and 6.

Like characters of reference designate like parts in the several figures of the drawings.

Referring first to Figs. 1 to 4 inclusive, 10 designates the end sill of a railway car of wood construction and 11 the longitudinal sills. The train pipe comprises two pipe sections 12, 12^a, to the latter of which the angle cock 13 is secured.

14 designates a bracket secured to one of the longitudinal frames 11 by any suitable means, for example, the bolts 15. The bracket is provided with a forwardly projecting part 16 which extends under the end sill 10 and is formed with a horizontally dis-

posed, preferably channel-shaped member 17 that lies transversely of the car and is perforated with the bolt holes 18^a. The extremities of the pipe sections 12, 12^a, are threaded and screwed into a coupling element 18 (Fig. 4) which is formed with a base 19 adapted to fit into the channel of the transversely extending member 17 and formed with bolt holes 20. The coupling element is secured to member 17 by bolts 21. Its position on the member 17 may be varied in accordance with the distance between the train pipe, the position of which relative to the longitudinal median line of the car is uniform for all cars, and the sill to which the bracket is secured.

In Figs. 5 to 7 inclusive the construction is modified so that the angle cock abuts against the coupling element. In this construction the forwardly projecting portion 22 of the bracket 23 is longer than the corresponding part of the bracket 14 just described. The bracket is provided with a transversely extending channel-shaped member 24 in which is seated a coupling member 25, the latter being preferably adjustably positioned as in the other construction. The train pipe comprises a section 12^b, the extremity of which is screwed into a threaded opening in one side of the coupling member, and a short section 12^c threaded at the outer end for the angle cock 13 and at its inner end so as to be screwed into the threading of an interior web 26 of the coupling member; the intent being that the section 12^c should be short enough so that the angle cock can be screwed up against the coupling member 25. The arrangements just described besides rigidly anchoring the end of the train pipe to one of the longitudinal sills of the car frame does away entirely with any overhang of the train pipe. The stress exerted on the angle cock by the weight of the hose and coupler heads and by the tautening of the coupling when the train rounds a sharp or reverse curve, is transmitted to the supporting bracket, which can be made as strong and heavy as necessary instead of being exerted against the train pipe.

While I have described my invention in certain preferred embodiments, modifications might be devised without departure from the principle of the invention. Therefore I do not wish to be understood as limiting the invention to the particular constructions, arrangements and devices shown and described except so far as the same are made specifically limitations in certain of the claims hereof.

I claim:

1. The combination with the under frame of a railway car comprising longitudinal sills and end sills, of a train pipe, means for attaching the train pipe to the under

side of the car comprising a bracket secured to one of said longitudinal sills near the extremity thereof which projects outwardly under the end sill, and engaging means for said train pipe on the projecting portion of said bracket.

2. The combination with the under frame of a railway car comprising longitudinal sills and end sills, of a train pipe, means for attaching the train pipe to the under side of the car comprising a bracket secured to one of said longitudinal sills near the extremity thereof which projects outwardly under the end sill, engaging means for said pipe, and means for adjustably anchoring said engaging means to the projecting portion of said bracket.

3. The combination with the under frame of a railway car comprising longitudinal sills and end sills, of a train pipe comprising two pipe sections and means for attaching the train pipe to the under side of the car comprising a bracket secured to one of the longitudinal sills near the extremity thereof which projects outwardly under the end sill, and a coupling element on the projecting portion of said bracket with which said pipe sections have a threaded engagement.

4. The combination with the under frame of a railway car comprising longitudinal sills and end sills, of a train pipe comprising two pipe sections and means for attaching the train pipe to the under side of the car comprising a bracket secured to one of the longitudinal sills near the extremity thereof which projects outwardly under the end sills, a coupling element with which said pipe sections have a threaded engagement, and means for adjustably anchoring said coupling element to the projecting portion of said bracket.

5. The combination with the under frame of a railway car comprising longitudinal sills and end sills, of a train pipe comprising two pipe sections and means for attaching the train pipe to the under side of the car comprising a bracket secured to one of the longitudinal sills near the extremity thereof which projects outwardly under the end sill and is formed with a channel-shaped member extending transversely of the car, a coupling element with which said pipe sections have a threaded engagement, and means for adjustably anchoring said coupling element to said channel-shaped member.

6. The combination with the under frame of a railway car comprising longitudinal sills and end sills, of a train pipe comprising two pipe sections, a bracket secured to one of said longitudinal sills, a coupling element with which said train pipe sections have a threaded engagement, and means for anchoring said coupling element to said bracket at different positions thereon.

7. The combination with the under frame of a railway car comprising longitudinal sills and end sills, of a train pipe comprising two pipe sections, a bracket secured to one of said longitudinal sills formed with a member extending transversely of the car, a coupling element with which said train pipe sections have a threaded engagement, and means for anchoring said coupling ele-
10 ment to the transversely extending member of the bracket at different positions thereon.

8. The combination with the under frame of a railway car comprising longitudinal sills and end sills, of a train pipe section, a bracket secured to one of said longitudinal sills near the extremity thereof, a coupling element on said bracket with which the end of said train pipe section has threaded engagement, an angle cock, and a short pipe
15 section which connects the angle cock with the coupling member so that the former bears against the latter.

9. The combination with the under frame of a railway car comprising longitudinal sills and end sills, of a train pipe section, a bracket secured to one of said longitudinal sills near the extremity thereof and projecting outwardly under the end sill, a coupling element on the forwardly projecting portion
25 of said bracket with which the end of the train pipe section has threaded engagement, an angle cock, and a short pipe section which connects the angle cock with the coupling member so that the former bears against
30 the latter.

10. The combination with the under frame of a railway car comprising longitudinal sills and end sills, of a train pipe section, a bracket secured to one of said longitudinal sills near the extremity thereof and having 40 a member extending transversely of the car, a coupling element with which the end of said train pipe section has threaded engagement, an angle cock, a short pipe section which connects the angle cock with the coupling element so that the former bears against the latter, and means for anchoring said coupling element to the transversely extending member of the bracket at different positions thereon.
45

11. The combination with the under frame of a railway car comprising longitudinal sills and end sills, of a train pipe section, a bracket secured to one of said longitudinal sills projecting forwardly under the end sill 55 and formed with a member extending transversely of the car, a coupling element with which the end of said train pipe section has threaded engagement, an angle cock, a short pipe section which connects the angle cock 60 with the coupling element so that the former bears against the latter, and means for anchoring said coupling element to the transversely extending member of the bracket at different positions thereon.
